TEXTILE FABRIC OR SIMILAR ARTICLE

Sergei Bogdanovich, Carmel, N. Y., assignor to Weil & Durrse, Inc., New York, N. Y., a corporation of New York

Application April 10, 1956, Serial No. 40,995

Term of patent 3½ years

(Cl. D92—1)

Fig. 1 is a face view of a textile fabric or similar article, showing my new design. The full width of the fabric is disclosed vertically and the design repeats along the length of the fabric as indicated horizontally on the drawing; and

Fig. 2 is an enlarged view of that portion of Fig. 1 which is indicated by the dot and dash area.

I claim:

The ornamental design for a textile fabric or similar article, as shown and described.
